BATH MITT

Randolph M. Rooker, Norlina, N.C.

Filed Jan. 18, 1966, Ser. No. 668

Term of patent 14 years

(Cl. D9—2)

FIG. 1 is a side elevational view of a bath mitt in flattened position, showing my new design;

FIG. 2, an elevational view of the opposite side thereof;

FIG. 3, an end elevational view thereof; and,

FIG. 4, a perspective view thereof taken on a reduced scale shown in normal use on the hand of the wearer, the broken lines indicating the wrist being for illustrative purposes only.

The broken lines shown on the mitt in FIGS. 1, 2 and 4 indicate stitching.

I claim:

The ornamental design for a bath mitt, as shown and described.
